UNITED STATES PATENT OFFICE.

JAMES ALEXANDER CARLTON, OF TORONTO, ONTARIO, CANADA, ASSIGNOR TO MASSEY-HARRIS COMPANY, LIMITED, OF TORONTO, CANADA.

SAFETY DEVICE FOR ELEVATORS.

Application filed August 18, 1927. Serial No. 213,817.

This invention relates to safety devices for elevators and more particularly to the type in which the elevator gate is adapted to lock and unlock the elevator and the elevator is adapted to lock and unlock the gate and my object is to provide a simple device of this character which may be manufactured cheaply and which may readily be applied to elevators now in service.

I attain my object by means of the constructions briefly described as follows. To the usual elevator control cable is secured a cable having a number of bars connected therein, one for each landing or floor at which the elevator may stop. Each bar has a plurality of slots formed therein, any one of which is adapted to receive an end of a spring pressed latch. Each elevator gate is provided with an arm adapted, when the gate is closed, to engage the latch to move it out of engagement with the bar and thus release the elevator control cable. Each gate arm is adapted to be locked, when the gate is closed, by another latch and these latches are adapted to be released by a shoe carried on the elevator. The latches located at each landing are carried in a casing or box through which passes the slotted bar and in one end of which is received the gate arm. The constructions are more fully described and illustrated in the accompanying drawing in which

Fig. 1 is a diagrammatic view showing the manner in which the bars are carried;

Fig. 2 a front elevation of the casing, partly broken away to show the latches;

Fig. 3 a cross section of the casing on the line 3—3 in Fig. 2;

Fig. 4 a long section on the line 4—4 in Fig. 2; and

Fig. 5 a longitudinal section on the line 5—5 in Fig. 2.

In the drawings like numerals of reference indicate corresponding parts in the different figures.

1 is an elevator control cable of ordinary construction arranged in the ordinary manner around pulleys 1^a and 1^b for controlling the operation of the elevator operating means (not shown). The ends of another cable 2 are secured to the first cable and in the cable 2 are connected a plurality of bars 3. These bars are located in the elevator well adjacent the landings 4.

Each bar is provided with a series of slots

3^a forming shoulders adapted to be engaged by a latch 3^b. The latch is pivoted intermediate its ends in a casing 5 and a coil spring 6 engaging the end 3^c of the latch tends to rock the latter into engagement with the shoulders.

To the usual sliding gate 7 at each landing is secured an arm 7^a. The end 7^b of the arm being adapted, when the gate is closed, to engage the latch end 3^c to rock the latch out of engagement with the slots 3^a. The gate is normally locked in its closed position by means of a latch 7^c adapted to engage the portion 7^e of the arm 7^a. This latch is also pivoted within the casing 5 and a spring 8 engaging the end 7^f of the latch tends to rock the latch to its operative position.

The gate latch 7^c is released by a shoe 9^a carried by the elevator 9, the shoe being adapted to engage the latch end 7^f, when the elevator is substantially in alignment with a landing.

The casing 5 is provided with slots 5^a and 5^b through which the spring engaging ends 3^c and 7^f of the latches 3^b and 7^c project for engagement by the gate arm 7^a and the elevator shoe 9^a respectively. The upper end of the casing, which is secured to a wall of the elevator well, is formed with two chambers 5^c and 5^d spaced apart to receive the upper ends of the latches 3^b and 7^c. The side walls of the chamber 5^d are cut away at 5^e to receive the portion 7^e of the gate arm 7^a. The latter is provided with two bends intermediate the portions 7^e and 7^b to form a laterally extending portion 7^d which extends substantially parallel to the side walls of the casing chambers 5^c and 5^d and lies in the space between them.

From the above description it is obvious that when the gates are closed they will be locked by the latches 7^c and that the gate arms 7^a will move the latches 3^b out of engagement with the bars 3. The elevator is now free and can be moved up or down by operating the control cable 1 in the usual manner. When the elevator reaches each landing the shoe 9^a releases the latch 7^c from engagement with the arm 7^a of the gate 7 at the landing whereby that gate may be opened. If the gate be opened the arm 7^a moved out of engagement with the latch 3^b and the spring 6 forces the latch into engagement with any one of the slots in the bar 3. This locking

of any of the bars 3 prevents the control cable from being operated until the gate is again closed.

What I claim is:

5 1. In a device of the character described, the combination with an elevator, an elevator control cable and a gate, of a bar connected with the cable and provided with a series of shoulders; a latch adapted to engage the 10 shoulders to releasably lock the bar; an arm carried by the gate adapted to engage the latch to move it to an inoperative position when the gate is closed; a latch adapted to engage the arm to releasably lock the gate in 15 its closed position; a shoe carried by the elevator for moving the gate locking latch to an inoperative position when the elevator is substantially in alinement with a landing.

2. An elevator and elevator gate locking 20 device comprising a casing; two latches pivotally carried within the casing, one being adapted to releasably lock an elevator control cable; an arm carried by an elevator gate adapted to move the cable locking latch to 25 an inoperative position and to be releasably locked by the other latch when the gate is closed; and a shoe carried by an elevator for moving the gate locking latch to an inoperative position when the elevator is at a landing.

3. In a device of the character described 30 the combination with an elevator, an elevator control cable and a gate, of a casing having two chambers arranged side by side in spaced 35 relationship to one another, the sides of one chamber being cut away, the casing being provided with slots; cable and gate locking latches pivotally carried within the casing and having their upper ends received in the 40 chambers, each latch having an end projecting through one of the slots; an arm carried by the gate adapted to engage the projecting

end of the cable locking latch to move it to release the cable, the arm being bent intermediate its ends to lie in the said cut away 45 portion of one of the chambers for engagement by the gate locking latch; and a shoe carried by the elevator for engaging the projecting end of the gate locking latch to release it when the elevator is at a landing.

4. In a device of the character described 50 the combination with an elevator, an elevator control cable and a gate, of cable and gate locking latches arranged side by side and having their latch jaws at opposite ends of 55 the latches; an arm carried by the gate adapted to engage the cable locking latch to release the cable when the gate is closed, the gate locking latch being adapted to lock the arm when the arm is in its cable latch releasing position; and a shoe carried by the elevator for moving the gate locking latch to an inoperative position when the elevator is substantially in alinement with a landing.

5. In a device of the character described 60 the combination with an elevator, an elevator control cable and a gate, of cable and gate locking latches arranged side by side and having their latch jaws at opposite ends of 65 the latches; an arm carried by the gate adapted to engage the cable locking latch to release the cable when the gate is closed, the arm being bent intermediate its ends for engagement by the gate locking latch when the 70 arm is in its cable latch releasing position, whereby the arm is positioned behind one latch and in front of the other; and a shoe carried by the elevator for moving the gate locking latch to an inoperative position when the elevator is substantially in alinement with 75 a landing.

Signed at Toronto, Canada, this 5th day of August, 1927.

JAMES ALEXANDER CARLTON.
